US0D1066238S

(12) **United States Design Patent** (10) **Patent No.:** **US D1,066,238 S**
(45) **Date of Patent:** **** Mar. 11, 2025**

(54) **LITHIUM BATTERY**

(71) Applicant: **Shenzhen Lepower Electronic Co., Ltd.**, Shenzhen (CN)

(72) Inventor: **Yongping Huang**, Guangdong (CN)

(73) Assignee: **Shenzhen Lepower Electronic Co., Ltd.**, Shenzhen (CN)

(**) Term: **15 Years**

(21) Appl. No.: **35/516,973**

(22) Filed: **Jan. 7, 2023**

(80) **Hague Agreement Data**

Int. Filing Date: **Jan. 7, 2023**

Int. Reg. No.: **DM/228190**

Int. Reg. Date: **Jan. 7, 2023**

Int. Reg. Pub. Date: **Apr. 28, 2023**

(51) **LOC (15) Cl.** **13-02**

(52) **U.S. Cl.**

USPC **D13/103**

(58) **Field of Classification Search**

USPC D13/102–106, 110, 118, 119, 184, 199;
D14/253, 432, 434

CPC H01M 6/00; H01M 6/14; H01M 6/10;
H01M 10/52

(57) **CLAIM**

The ornamental design for a lithium battery as shown and described.

DESCRIPTION

The patent or application file contains at least one drawing executed in color. Copies of this patent or patent application publication with color drawing(s) will be provided by the Office upon request and payment of the necessary fee.

1. Lithium battery

1.1 : Front

1.2 : Back

1.3 : Left

1.4 : Right

1.5 : Top

1.6 : Bottom

1.7 : Perspective

The broken lines in the drawings are for the purpose of illustrating portions of the article that form no part of the claimed design.

1 Claim, 7 Drawing Sheets
(7 of 7 Drawing Sheet(s) Filed in Color)
